UNITED STATES PATENT OFFICE.

ARTHUR LAVERN ADEE, OF VANCOUVER, WASHINGTON, ASSIGNOR TO H. W. ARNOLD,
R. C. SUGG, AND FELIX ROBINSON.

DEVICE FOR ATTACHING A CHILD'S NURSERY TOILET-SEAT TO THE SEAT OF AN ORDINARY TOILET.

1,296,901.

Specification of Letters Patent. Patented Mar. 11, 1919.

Application filed March 1, 1917. Serial No. 151,851.

To all whom it may concern:

Know all men by these presents that I, ARTHUR LAVERN ADEE, native-born citizen of the United States, residing in the city 5 of Vancouver, county of Clarke, and State of Washington therein, have invented certain useful and new Improvements and Devices for Attaching Children's Nursery Toilet-Seats to the Seats of Ordinary 10 Toilets, of which the following is a specification.

My invention relates to certain new and useful improvements and devices for attaching quickly and easily a substantial child's 15 nursery toilet seat to the seat of an ordinary toilet in such a way that it may be easily detached and used repeatedly. My invention is adapted to other uses, but particularly in connection with attaching a child's 20 nursery toilet seat to the seat of an ordinary toilet in such a way as to hold it firmly and securely in position, so that it will not tip over, slide off, or come loose, until the operator desires to have it removed, when the 25 necessity for its use no longer exists.

The object of this invention is to produce a device of this character which is simple in construction, composed of few parts, not likely to get out of order, and which can 30 be easily, quickly and securely attached to the seat of any ordinary toilet for the use of small children particularly, and which may be detached and removed quickly and easily when not required.

With these and other objects in view, my invention consists of certain constructions, combinations, arrangements, parts, and the method, manner and means of attaching and securing the same, the preferred form 40 of which will first be described in connection with the accompanying drawing and the invention particularly pointed out in the appended claims.

I will first describe the different parts or 45 members of this device and to describe the methods of applying and using the same will take as an illustration a diagram of a child's nursery toilet seat and also the seat of an ordinary sanitary toilet. Referring now to the drawings hereto attached and made a part of this application, wherein there has been illustrated the preferred form and construction of my invention as it is reduced to practice, throughout the

different views of which similar reference 55 numerals designate similar parts—

Figure I is a front elevation of the said nursery toilet seat in position on the seat of an ordinary toilet, showing the hooks or clamps which are the subject of this invention engaged with and in place on the toilet seat.

Fig. II is a side elevation of the said nursery toilet seat, showing one of the said hooks at the right side of the said nursery 65 toilet seat, which is disengaged from the toilet seat on which it is intended to be used.

Fig. III shows the upper or top side of the said nursery toilet seat set up and in position, showing in dotted lines on either 70 side the location and position of the hooks for which this patent is applied.

Fig. IV shows the nursery toilet seat in a collapsed form, with the hooks which are the subject of this application folded 75 over as they may be folded when not in use.

For convenience in describing the application and use of my invention, I will take for illustration a folding nursery seat which consists of a back member, 10, and two side 80 members or arms, 12 and 13, that may be collapsible by being attached to the back member with hinges 12' and 13' so that both of the outside members fold inward. The seat or bottom member, 11, of this nursery 85 toilet seat is preferably made of a flat board, and is provided with an opening of suitable size and convenient form which is connected with the back member by a hinge joint, 11', at the back so that it can be raised up 90 against the back member, and when so raised up the side members folded in against it. The hooks which are the subject of this invention are designed to be attached to the side members of such a nursery toilet seat 95 in such a way that when the side members are extended by opening outwardly and the bottom member, 11, is let down to a horizontal position, the side members and hooks are firmly locked in position, or when it is 100 not used in a collapsible nursery toilet seat, they are attached to a nursery toilet seat that has solid sides and bottom, and either form of nursery toilet seat or chair may be set upon the opening of the toilet seat of the 105 ordinary form so that the hooks in line are practically parallel with the longest dimension of the opening of the toilet seat, then

the nursery toilet seat is turned at right angles facing forward, so that the hooks engage the under side of the toilet seat, thereby holding it firmly in place.

- 5 These hooks or clamps which are the subject of this application are preferably made of metal, with a straight shank extending upward on the outside of the side members of the toilet seat and are attached thereto 10 by means of screws or nails, which are inserted through the shanks of the hooks and into the side members, holding them firmly and permanently in place. These hooks then extend inward from their connection 15 and downward and then outward in such a way that when they are in position the hooks will catch toward the outward side of the side member rather than other direction.
- 20 In the diagrams above referred to, the back member of the toilet chair or nursery toilet seat is designated by 10, the side members are designated respectively by 12 and 13, the seat or bottom member designated 25 by 11. The hooks which are the subject of this invention are designated as 16 and 17, and the toilet seat to which this nursery seat is to be attached is designated in cross section in Fig. 1 by 18 in dotted lines.
- 30 Having thus described my invention, what I claim and desire to secure by Letters Patent is:—
1. A removable nursery seat arranged for application to a toilet article having a 35 flanged opening, comprising a back member and foldable bottom and side members having hinged connections with said back member whereby as said bottom member is swung to open position it will force said hinged 40 side members outwardly, means associated with said hinged bottom member to lock said side members in open position, and out-

wardly facing hooks carried by said hinged side members adapted to be urged into engagement with the flanged opening of the 45 toilet article as said side members are swung outwardly.

2. A removable nursery seat for a toilet article having a flanged opening, comprising a back member and foldable bottom and side 50 members having hinged connections with said back member whereby as said bottom member is swung to open position it will force said hinged side members outwardly, and means associated with said hinged members 55 to lock said side members in open position and in engagement with said flanged opening.

3. A removable nursery seat for a toilet having a flanged opening, comprising 60 a rigid back member, a bottom member hinged along the lower edge thereof, and side members hinged to each side of the back member adapted to inclose the bottom member when swung upwardly parallel to 65 the back member, said bottom member having notches at its forward edge adapted to coact with said side members and urge the same outwardly as the bottom member is moved to right angle position with respect 70 to the back member, thereby to hold said side members against either inward or outward movement with respect thereto, and hooks carried by one of said parts adapted to coact with the flanged opening of the 75 toilet.

In testimony whereof I affix my signature in the presence of two witnesses, this Feb. 14, 1917.

ARTHUR LAVERN ADEE.
